UNITED STATES PATENT OFFICE.

CHARLES F. BRAND, OF WHEELING, WEST VIRGINIA.

GAS-BURNER.

1,348,261.

Specification of Letters Patent.

Patented Aug. 3, 1920.

Application filed October 20, 1919. Serial No. 331,899.

To all whom it may concern:

Be it known that I, CHARLES F. BRAND, a citizen of the United States of America, and resident of Wheeling, county of Ohio, 5 and State of West Virginia, have invented certain new and useful Improvements in Gas-Burners, of which the following is a specification.

This invention relates broadly to gas 10 burners, and more particularly to a manifold for gas burners.

The primary object of the invention is to provide a simple and compact distributor manifold for gas burners of the multiple-burner type more or less commonly employed in the furnaces of steam, hot water and hot air heating systems for buildings.

A further object is to provide a manifold of the character mentioned which is adapted for supplying either all of the various burners carried thereby or alternate burners only, as desired.

With these and other important objects in view, the invention resides in the features of construction, arrangement of parts 25 and combination of elements which will hereinafter be fully described, reference being had to the accompanying drawings, in which—

Figure 1 is a side elevation of the invention, showing some of the burners omitted from the manifold;

Fig. 2 is a partial horizontal section of the manifold; and—

Figs. 3 and 4 are sections taken respectively on lines 3—3 and 4—4, Fig. 2.

Referring to said drawings, in which like designating characters distinguish like parts throughout the several views—

1 indicates generally a manifold consisting of a circular one-piece metal casting which is cored out interiorly to provide two separate chambers 2 and 3. Said chambers are located in superposed non-communicating relation, being separated throughout by a horizontal division wall 4. Said chambers are further located annularly with respect to a central hub-like portion 5 of the casting, being disposed between said portion and a circular vertically-disposed web 6 which is located concentric with respect to said hub-like portion and at a suitably spaced distance from the outer peripheral wall 7 of the casting.

Leading vertically to the interior of the lower chamber 3 through the bottom wall 8

of the casting is a threaded hole 9 in which is received the upper end of a pipe 10 which constitutes a branch of a gas-supply pipe 11; and leading upward to the interior of the upper chamber 2 through said bottom wall 8, the division wall 4 and an integral tubular member 12 located between said walls 4 and 8 is a passage 13, threaded at its lower end, in which is received the upper end of a branch supply pipe 14.

The peripheral wall 7 of the manifold has extending therethrough a plurality of uniformly spaced radially directed threaded openings or holes 15 adapted for the reception of the threaded inner ends of suitable individual gas burners 16, or of short lengths of pipe 17 upon which said burners are mounted, said manifold being thus adapted to be encircled by a cluster of 75 burners. Said holes 15 communicate at their inner ends with passages 18 aligned therewith which are located between the circular web 6 and the peripheral wall 7 and which are separated by vertical radially disposed webs 19 which extend from the top wall 20 to the bottom wall 8. Said passages, except two diametrically opposite passages 18^a, Figs. 2 and 4, alternately communicate with the chambers 2 and 3 through 80 passages 2^a and 3^a, as shown in Figs. 2 and 3.

Formed on the top wall 20 of the manifold is a diametrically disposed rib 29 which is cored out interiorly to form a passage 21 90 which communicates at its opposite ends with the opposite passages 18^a, hereinbefore referred to, through ports 22 formed in said top wall.

Leading vertically upward through the 95 central hub-like portion of the manifold and communicating at its upper end with said passage 21 is a central bore 23 which is threaded at its lower end for the reception of an end of a branch supply pipe 24.

The holes 15 which lead outward from the two passages 18^a are designed to receive burners which are continuously supplied with gas from the branch pipe 24 and serve as pilots which may remain lighted when 105 the gas is shut off from the burners which are supplied from the branch pipes 10 and 14 through the chambers 3 and 2, respectively. Key-operated valves 25 and 26 are preferably provided on said pipes 10 and 110 14, respectively, whereby the supply of gas through said pipes may be regulated or en-

- tirely shut off. Or, a thermostatically controlled valve, as the snap valve 27, may be provided on the supply pipe 11 whereby regulation of the gas supply may be controlled. A valve 28 may be provided on the pilot supply pipe 24 to be closed when use of the heater is discontinued. When the thermostat-controlled valve 27 is employed, the same is located forward of the point of attachment of the pilot pipe 24 with the supply pipe 11, as shown in Fig. 1, so that the supply of gas furnished through said pilot pipe will not be affected by operation of said valve.
- From the foregoing description it will be obvious that various combinations of the burners 16 may be employed. With twenty-four burners mounted on the manifold, as shown, in Fig. 1, the entire number may be utilized for furnishing heat; or, by shutting off the two pilot burners, the number may be reduced to twenty-two. With the valve 26 closed, cutting off the burners supplied through the upper chamber 2, but fourteen burners are supplied, and this may be reduced to twelve by shutting off the supply to the pilot burners. With the valve 25 closed, cutting off the burners supplied through the lower chamber 3, twelve burners are supplied, and this may be reduced to ten by shutting off the supply to the pilot burners. Or, both valves 25 and 26 may be closed, leaving only the two pilot burners lighted.
- The three branch pipes 10, 14 and 24 serve as supports for the manifold which is mounted directly thereon.
- Among various advantages afforded by the manifold described, one of the most important and one which instantly appeals to those skilled in the heating art is the ease and facility with which it may be installed, as compared with the burners commonly employed.
- What is claimed is—
1. A multiple-burner manifold for furnaces, comprising a body having therein separate inclosed chambers located in superposed relation at a suitable distance from its outer edge wall, said edge wall having therein a plurality of holes adapted for the reception of individual burner elements, an inclosed radially disposed passage for each of said holes and communicating with the latter at its outer end, said passages having alternate communication at their inner ends with the upper and lower of said chambers, and separate supply passages leading to said chambers.
  2. A multiple-burner manifold for furnaces, comprising a body having a central hub-like portion encircled by separate inclosed chambers located in superposed relation and at a suitable distance from its outer edge wall, said wall having therein a plu-

rality of radial openings for the reception of individual burner elements, separate radially disposed passages with which said openings communicate, alternate passages being in open communication at their inner ends with the upper and lower of said chambers respectively, and separate supply passages leading to said chambers.

3. A multiple-burner manifold for furnaces, comprising a body having a central hub-like portion encircled by separate inclosed chambers located in superposed relation and at a suitable distance from its outer edge wall, said wall having therein a plurality of radial openings for the reception of individual burner elements, separate radially disposed passages with which said openings communicate, one or more of said passages being adapted to supply pilot burners therethrough, means for conducting gas to the last-mentioned passages, the remainder of said passages communicating at their inner ends with the upper and lower of said chambers in alternation, and separate supply passages leading to said chambers.

4. A multiple-burner manifold for furnaces, comprising a body having a central hub-like portion encircled by separate inclosed chambers located in superposed relation and at a suitable distance from its outer edge wall, said wall having therein a plurality of radial openings for the reception of individual burner elements, separate radially disposed passages with which said openings communicate, one or more of said passages being adapted to supply pilot burners therethrough, said hub-like portion having a passage therethrough adapted for the reception of an end of a supply pipe and communicating suitably with the last-mentioned passages, the remainder of said passages communicating at their inner ends with the upper and lower of said chambers in alternation, and separate supply passages leading to said chambers.

5. A multiple-burner manifold for furnaces, comprising a body having a central hub-like portion encircled by separate inclosed chambers located in superposed relation and at a suitable distance from its outer edge wall, said wall having therein a plurality of radial openings for the reception of individual burner elements, separate radially disposed passages with which said openings communicate, one or more of said passages being adapted to supply pilot burners therethrough, said hub-like portion having a passage therethrough adapted for the reception of an end of a supply pipe, a diametrically disposed rib formed on a face of said body, a passage formed in said rib communicating at its opposite ends with said pilot supply passages and intermediate its ends with the passage in said hub, the remainder of said radial passages communicat-

ing at their inner ends with the upper and lower of said chambers, respectively, in alternation, and separate vertical supply passages leading to said chambers.

- 5 6. A gas burner for furnaces, comprising a circular manifold having two chambers therein located in superposed relation, a plurality of individual burners mounted peripherally on said manifold, one of said burners constituting a pilot, a radial passage 25 leading to each burner, said radial passages, excepting that leading to the pilot burner, being in communication with the upper and lower of said chambers in alternation, two 30 separate gas supply pipes leading to said chambers, and a third supply pipe having communication only with the radial passage which leads to the pilot burner.
- 10 15 7. A gas burner for furnaces, comprising separate supply passages through which gas is conducted to said chambers, and a third supply passage through which gas is conducted to the radial passage which leads to the pilot burner.

- 20 7. A gas burner for furnaces, comprising

a circular manifold having two chambers therein located in superposed relation, a plurality of individual burners mounted peripherally on said manifold, one of said burners constituting a pilot, a radial passage 25 leading to each burner, said radial passages, excepting that leading to the pilot burner, being in communication with the upper and lower of said chambers in alternation, two 30 separate gas supply pipes leading to said chambers, and a third supply pipe having communication only with the radial passage which leads to the pilot burner.

In testimony whereof, I affix my signature in presence of two subscribing witnesses.
